Inventor;
J. Theodor. Chabot.

UNITED STATES PATENT OFFICE.

J. THEODORE CHABOT, OF BUFFALO, NEW YORK.

SHIP'S TILLER.

Specification of Letters Patent No. 26,650, dated January 3, 1860.

To all whom it may concern:

Be it known that I, J. THEODORE CHABOT, of the city of Buffalo, in the county of Erie, in the State of New York, have invented 5 new and useful Improvements in Steering Apparatus; and I do hereby declare that the following is a full and exact description thereof, reference being had to the accompanying drawings, and to the letters of reference marked therein, making a part of 10 this specification, in which—

Figure 1 is a top side view of the deck V of vessel, illustrating the arrangement of the steering wheel M, connected to a straight 15 tiller E and double blocks y, y; Fig. 3 the upper and lower shells of block y y with strap z. Fig. 2 the upper and lower straps c, c. One way v, roller x and one block y, shell t and rollers; same letters referring to 20 like parts in all of the drawings.

The nature of my improvements consists in arranging the double blocks y y with the 25 sliding block t, t, upon the forward end of straight tiller E, moving upon the square surface P, of tillers, as an advantage gained in controlling vessels.

To enable others skilled in the art to make and use my invention I will proceed to 30 describe its construction and operation.

Fig. 1 the chain makes five turns around the drum L part of which h extending downward underneath the friction pulley b, passing to the left and around the stationary pulley e, at right angle; also to and around 35 the rear stationary pulley e s around the left block y, and united to a stationary point, W, near the sheave or pulley e s. The other part of chain K extending downward and underneath its pulley b and to and around 40 the right stationary pulley t a of the stationary block c at a right angle, passing to the rear parallel with the deck V, to and around the right stationary pulley e s and to and around the right block y; and to the right 45 stationary point W. A portion of the chain h, k may be supplied at the center with the rods J J'. The surface of straight tiller bar E, from the point of its connection to the side bars F, F, extending forward to the 50 stay box n', is flattened, forming a parallelogram and for the horizontal movement of the sliding block t t of tiller E. The sliding block t, t, is composed of an upper

and lower shell with friction rollers located between, and at each end of the shells t, t, as 55 seen in Fig. 2. The block t, t, is also united by an upper and lower strap c, c, as also seen in Fig. 2, with the attachment of the left block, y, and encompassing the lower shells t in Fig. 2, and the tiller center beam E, as 60 also seen in Fig. 1.

The upper shell t and strap c, are united by a center bolt, as well as the lower shell t and strap c, separately. The screw swivels r, r', may be connected to the chain h and 65 K, at the stationary points W, W. The upper center bolt has a friction roller X inserted; moving upon the surface of the ways or way o, which may be united to deck 70 of vessel, as seen in Fig. 2.

Operation: The straight tiller is moved right and left by its connection to steering wheel M with chain h rod J, and the other part K and rod J, as seen in Fig. 1, arranged underneath the deck V of vessel in part; 75 a portion of the deck being left off, in order to present the same. The double blocks y, y with sliding block t t, moves right and left upon the surface P of tiller; thereby the tiller E is permitted also to swing left and 80 right, as indicated by the dotted lines N. The power of tiller E; or lever is increased in proportion to the draft of water upon the rudder blade, as the tiller is moved either right or left from midship. The rear portions of chain h and K move upon a straight line, while the movements of tiller E describe a circle, from the rudder post as its center. The straight tiller E may be used without the sliding blocks X X or with the 85 90 sliding blocks X X.

What I claim as my invention and desire to secure by Letters Patent is—

The surface P of the forward end of straight tiller E in form representing a parallelogram, in combination with the sliding block t t and its friction rollers; double block y, y, lower and upper strap c, c, with center bolts located at the center of tiller E; as described in the foregoing specification. 95 100

T. THEODOR CHABOT.
